DESIGN FOR A COMBINED LETTER OPENER AND MAGNIFIER

Leo L. Kay, Milwaukee, Wis.

Application October 14, 1944, Serial No. 115,785

Term of patent 7 years

(Cl. D74—1)

To all whom it may concern:

Be it known that I, Leo L. Kay, a citizen of the United States, residing at Milwaukee, in the county of Milwaukee and State of Wisconsin, have invented a new, original, and ornamental Design for a Combined Letter Opener and Magnifier, of which the following is a specification, reference being had to the accompanying drawing, forming part thereof.

In the drawing:

The handle is transparent.

I claim:

The ornamental design for a combined letter opener and magnifier, as shown and described.

LEO L. KAY.
